UNITED STATES PATENT OFFICE.

WILLIAM E. VOSS, OF OKLAHOMA, OKLAHOMA.

LOW-PRESSURE ALARM.

1,300,523.

Specification of Letters Patent. Patented Apr. 15, 1919.

Application filed April 10, 1916. Serial No. 90,184.

To all whom it may concern:

Be it known that I, WILLIAM E. Voss, a citizen of the United States, residing at Oklahoma, in the county of Oklahoma and State of Oklahoma, have invented certain new and useful Improvements in Low-Pressure Alarms, of which the following is a specification, reference being had to the accompanying drawings.

10 The object of the invention is to provide means for giving a signal when the pressure in a train-pipe is too low.

The accompanying drawings show one form in which the invention has been put in 15 actual practice.

Figure 1 is an elevation view showing a portion of a train-pipe and showing the invention in use thereon.

Fig. 2 is an enlarged view, mostly in section, showing the position of the parts of the 20 invention when the train-pipe is under normal pressure.

Fig. 3 is a fragmental view, mostly in section, showing the position of the parts when 25 the pressure has been reduced.

Fig. 4 is a similar view showing the position of the parts after further reduction of the pressure.

All the views are taken in the same direction, and like characters of reference designate like parts in all of them.

The numeral 5 designates the train-pipe of a car.

A cylinder 6 is placed in communication 35 with the train-pipe 5 by a pipe 7.

The cylinder 6 is fitted with a piston 8 whose rod 9 extends upward and slidably through a sleeve 10, the latter being screw-threaded through the upper end 11 of the 40 cylinder.

For convenience in construction and assemblage of parts, the upper end 11 of the cylinder 6 screws removably into place.

A compression helical spring 12 which 45 braces the rod 9 is interposed between the sleeve 10 and piston 6, and acts yieldably to force the latter downward in opposition to the pressure from the train-pipe 5.

The cylinder 6 is so arranged that when 50 the piston 8 is at an intermediate point of its full throw the air may by-pass it upward and operate a suitable alarm.

In arranging for this by-pass of air, a

port 13 in the form of a groove may be provided on the inner surface of the cylinder 6 55 and made longer than the piston 8.

The alarm may be in the form of a whistle 14 which forms an outlet from the cylinder 6 above the piston 8 and is sounded by escaping air.

With the train-pipe 5 under normal pressure the piston 8 is held to or toward the upper end of its throw in opposition to the spring 12 and covers the upper end of the 60 port 13 as shown in Fig. 2.

If the pressure of the train-pipe 5 be continually reduced, the spring 12 will gradually force the piston 8 downward until both ends of the port 13 are uncovered, as shown in Fig. 3; and the air thus allowed to 65 by-pass the piston 8 sounds the whistle 14.

A further reduction of pressure allows the piston 8 to be forced further downward by the spring 12 and cover the lower end of the port 13 in the position shown in Fig. 4, thus 70 stopping the by-pass of air and the sounding of the whistle 14 during the lowering of the pressure to zero.

With the parts of the device arranged and operating as shown and described, the 75 motorman is not only warned of reducing pressure at a point intermediate full normal pressure and zero, but when the compressor or other means of raising and maintaining air pressure begins to work, the increasing 80 pressure gradually raises the piston 8 back upward against the action of the spring 12 until both ends of the port 13 are again uncovered, the air again escaping through the port 13 and through the whistle 14 and 85 indicating that compression is taking place.

The further increase of pressure toward 90 normal raises the piston 8 to where it covers the upper end of the port 13 and stops the sounding of the whistle 14; and since it is 95 not necessary that the piston move farther upward any suitable means for limiting movement of said piston may be provided, for example the spring 12 in its fully compressed position shown in Fig. 2.

The outlet opening of the whistle 14 should be enough larger than that of the port 13 to prevent setting up of a balancing pressure above the piston 8.

The upper end of the rod 9 may be provided with a knob 15, and by an occasional

downward blow on this knob by the hand a motorman or engineer may keep the piston 8 from becoming stuck in the cylinder 6.

Having thus described the invention, I 5 claim:

1. The combination with a fluid pressure container, of a cylinder having one end thereof in communication with the container, a sleeve adjustably threaded in the 10 head at the opposite end of the cylinder, a piston rod slidable through the sleeve, a piston rigid with the piston rod and slidable within the cylinder, the interior of the cylinder being formed at one side thereof with a by-pass of which the end portions communicate with the cylinder at points spaced apart a greater amount than the thickness of the piston, and a spring surrounding the piston rod and interposed between the sleeve 15 and the piston, said spring tending to move the piston against the air pressure and the tension of the spring being adjustable by manipulating the before-mentioned sleeve, a lateral discharge opening being formed 20 in that end of the cylinder remote from the connection with the fluid pressure container, and alarm means actuated by the escape of air through the discharge opening.
2. The combination with a fluid pressure 25 container, of a cylinder having one end thereof in communication with the container, a piston rod slidable through the head at the opposite end of the cylinder, a piston mounted within the cylinder and connected to the piston rod, the interior of the cylinder being formed at one side thereof with a by-pass of which the ends communicate with the cylinder at points spaced apart 30 a greater distance than the thickness of the piston, a lateral discharge opening having 35 a whistle formed in connection therewith being provided in that end of the cylinder 40

remote from the connection of the cylinder with the pressure container, and a spring surrounding the piston rod and acting upon 45 the piston to move it against the air pressure.

3. The combination with a fluid pressure container, of a cylinder having one end thereof in communication with the container, a piston rod slidable through the 50 opposite end of the cylinder, a piston mounted within the cylinder and connected to the piston rod, the interior of the cylinder being provided at one side thereof with a by-pass of which the ends communicate 55 with the cylinder at points spaced apart a greater distance than the thickness of the piston, a spring normally tending to move the piston against the air pressure, the end of the cylinder remote from the connection 60 with the container being formed with a discharge opening, means actuated by the escape of air through the discharge opening to give an alarm, and a hand knob applied to the piston rod for preventing sticking of the 65 piston within the cylinder.

4. The combination with a fluid pressure container of a cylinder placed in communication therewith, a piston mounted within the cylinder, a piston rod connected with 70 the piston and projecting exteriorly of the cylinder, yielding means tending to move the piston in opposition to the pressure within the container, means for causing the fluid to pass around the piston and actuate 75 an alarm when the piston is brought to a predetermined point in the cylinder, and a knob on the piston for manually moving the piston to prevent sticking thereof in the cylinder.

Witness my hand this 5 day of April, 1916.

WILLIAM E. VOSS.
